UNITED STATES PATENT OFFICE.

JAMES E. GILLESPIE, OF BOSTON, MASSACHUSETTS.

IMPROVEMENT IN MACHINES FOR MAKING HYDRAULIC AND OTHER HOSE PIPES.

Specification forming part of Letters Patent No. **173,616**, dated February 15, 1876; application filed October 25, 1875.

To all whom it may concern:

Be it known that I, JAMES E. GILLESPIE, of Boston, in the county of Suffolk and State of Massachusetts, have invented an Improvement in Machines for Manufacturing Hydraulic and other Hose Pipe, of which the following is a specification:

This invention relates to a mechanism for manufacturing india-rubber-lined hose for hydraulic and other purposes, and is an improvement on Patent No. 163,925, June 1, 1875, granted to me.

In such machine the warp-carriers have pivoted inclined feet adapted to fit grooves in a rotating surface or plate, and the feet cross each other as the carriers are moved by the action of the plate to form sheds in the warp for the passage of the weft-threads that pass through guides projecting from the rotating plate and adapted to lay their threads as wefts between the warps.

In this present invention like carriers and feet are employed, and they operate in the grooves in the plate in the same way, but the walls surrounding the grooves in the plate are formed and cut, as will be hereinafter described, to throw the carrier quickly across the point of the crescent or dividing ledge between the grooves in the plate. This construction of the plate forms one feature of this invention.

The invention also consists in a tension device supported on the carrier and adapted to bite and hold the warp-thread until released by the carrier-weight; also, in mechanism to fold a piece or strip of india-rubber, or its equivalent, about a mandrel, into which steam may be introduced, lapping one edge of the strip over the other, the lapping being in the direction of the length of the tube, and in connection with such an apparatus I employ a mechanism for weaving a fibrous covering over the india-rubber, to be formed as herein-after set forth.

Figure 1 is a side elevation of a machine embodying this invention. Fig. 2 is a top view of the warp-carrier-operating grooved plate; Fig. 3, a carrier detached and enlarged; Figs. 4 and 5, views of the warp-tension device; Figs. 6 and 7, the weft-tension; and Fig.

8, a detail of the mandrel, over which the tube is formed.

In this invention the frame of the loom is of suitable size and shape, having extending from the lower plate a^1 to and above the upper plate a , a hollow shaft, a^2 , this shaft being connected with the hub of the lower plate by the screw b , and at or near the upper end of the hollow shaft is secured a hub, b^1 , having projecting therefrom a rest-plate, b^2 , on a level with the top plate a , and provided with holes c , for attachment of the forked warp-carrier guides c^1 , each guide being held by a screw passing therethrough and into the holes c . In Fig. 2 is shown in dotted lines one pair of these guides. These guides receive the heads c^2 of the warp-carriers, one shown detached in Fig. 3, and the pivoted feet d project into grooves d^1 d^2 , formed in the warp-carrier-actuating plate e , arranged at top of a sleeve e^1 , provided with a gear, e^2 , and fitted about and so as to turn on the hollow shaft a^2 , the plate e deriving motion from the gear f on the main shaft f^1 , operated in any suitable way. This plate e carries the weft-guides f^2 , the pivoted feet d rest in the grooves d^1 d^2 , and, as the plate rotates, the warp-carriers are crossed from one guide, c^1 , to its opposite guide and across the groove between the ends of the carrier guides, in which the weft-guides travel, all in the manner described in the patent referred to, to which reference is made, the warp and weft threads passing over the cup g , also used in such patent, and provided with a pipe, g^1 , supplied with liquid or plastic india-rubber, or its equivalent, or suitable water-proofing or cementing material, to be forced through the pipe g^1 into the cup g , and against and between the india-rubber lining g^2 and outer woven covering h . In this instance the cup g is separate from the mandrel h^1 , about which the india-rubber lining g^2 is formed, and the fibrous covering is woven, and it is supported by the standard h^2 and the pipe g^1 , the latter passing out through the bottom of the shaft a^2 , (see Fig. 1,) and receiving its india-rubber solution from a proper source. The mandrel h^1 is connected by means of a projection, i , with the hub b^1 , and stands above and substantially in a line with the opening in the hollow shaft a^2 ,

while attached to another portion of such hub by a projection, i^2 , is a longitudinally slotted folding guide, i^1 , and the india-rubber lining led into the lower end of the hollow shaft a^2 is folded about the mandrel h^1 by means of the guide i^1 , surrounding, but not touching, the mandrel.

This rubber lining is shown in section-lines in Fig. 2, with the mandrel within and the guide outside of it, the edges of the india-rubber being lapped one over the other. A presser-roller, j , on an adjustable arm, j^1 , controlled by a screw, j^2 , presses the lapped edges of the india-rubber together, such edges having been previously wet or moistened, preferably with benzine or equivalent, or with suitable cement, to cause the edges to unite firmly and form a water-proof seam or lap.

I may heat the inner side of the mandrel or the guide by passing steam or water through a pipe, as at k .

I intend to apply benzine, or a preparation thereof, or other softening material, to the edges of the india-rubber, during the process of folding, by means of a brush, or through a fibrous strand, placed one end in the moistening fluid, and the other end, by capillary attraction, depositing the liquid on the edges; or the edges may be moistened at any previous period; and I complete the joining of the edges by pressure, and with or without heat, as may be desirable.

This mandrel, at its upper end, is made as an annular chamber, k^1 , into which the sleeve or water-pipe k is led, and inside the chamber is placed a pipe, k^2 , open at top, and into and from the open top of which, and within the india-rubber lining, may be blown chalk or its equivalent, the same being allowed to drop and cover or coat the inner side or surface of the lining material, to prevent it from sticking to the mandrel. After the lining is folded or made into a tube the covering h is woven thereon, and a quantity of liquid india-rubber, or an india-rubber or cementing compound of any well-known kind, or such as used when securing rubber within fibrous tubes, being expressed from an annular opening in the top of the cup g , between the lining g^2 and covering h , the preparation forced between the lining and cover being preferably such a preparation of india-rubber as will vulcanize and cause a firm and close adhesion and union of the covering and lining.

Referring to Fig. 2, the plate e is designed to rotate in the direction of the arrow there on; and it will be noticed that the ends l of the crescent-shaped or dividing ledges l^1 are sharper than the edges l^2 , and pieces m m^1 , forming the walls of the grooves d^1 d^2 , are undercut, as shown in dotted lines, Fig. 2, and between the ends l l^2 are placed adjustable pieces m^2 , with friction-rollers n .

When the part o of a pivoted foot of a warp-carrier is to pass from either of the positions n^1 of either groove to either position n^2 , or to

cross the points where the two grooves intersect, then one of the small anti-friction rollers n , or a projection on m^2 , meets the forward portion of the pivoted foot at one side, and throws it quickly to the side of the end l farthest from it, the enlarged or thickened end l^2 of the crescent-shaped ledge l^1 acting at the same time on the opposite side of the foot, back of its pivotal point, throwing the free end of the foot quickly away, or so that it passes into the cut-away or recessed parts of the walls of the pieces m or m^1 , thereby rendering the crossing of the feet from one part of the groove to another part more rapid and certain, thereby preventing the carriers from dwelling so long as to become caught when passing from an outer to an inner carrier-guide, and crossing the usual circular groove or path w , in which the weft-guides move. With this construction the carriages are changed more rapidly than usual, and the loom may be run faster.

Each warp-thread passes from a spool, o^1 , through a hole in a guide, o^2 , on which (and free to slide) is a carrier-weight, p , provided with a roller, p^1 . A tension-lever, p^2 , is pivoted to the guide o^2 , and a spring, q , acting on the adjusting screw or device q^1 , bears the shoulder q^2 (see Fig. 4) of the lever p^2 with the desired force against the warp-thread which passes between the guide o^2 and shoulder q^2 . The warp, after passing through the hole in guide o^2 , is passed between the shoulder q^2 and the guide, then over and in the grooved portion r of the lever p^2 , about the roller p^1 , over the roller r' to the weaving-point. The weight p takes up and holds the slack warp; but when the slack is used up the weight is raised, and strikes the end of the lever, rocks it, and releases the warp from the action of the lever, and, after the formation of enough slack warp, the weight descends, releasing the lever and the spring q , then moves the lever to bite the thread.

A detail of the weft-tension is shown in Fig. 6. Each weft-thread passes from a spool, s , over and about a tension device composed of a truncated cone, s^1 , with a connected hub, s^2 . The weft is wound from the larger to the smaller end of the cone so as to gradually crowd the coil down the cone, yet not to permit the strands to overrun each other.

About the hub is placed a yielding compensating strap, t , preferably of light metal, one end being fixed and the other being passed through a slot or opening in a standard, t^1 , where it is provided with a spring, t^2 , one end of the spring resting against the standard and the other being controlled by a nut, u .

With friction devices as ordinarily constructed, if the surfaces of the hub and spring, or either, become gummed or coated with impurities, the spring sticks to the hub, it cannot yield, and the tension device being held rigidly, causes the thread to break. With the compensating-strap, should the strap ad-

here to the hub, the spring will yield and allow the tension-device or wheel to turn, and the strap being then loosened will allow the wheel and hub to move.

This device is applicable for use as a tension for the thread in a sewing-machine. Instead of the truncated cone, I might use any ordinary tension-wheel common to sewing-machine tensions, arranging a hub in connection therewith.

The grooved plate shown moves the carriers for plain weaving; but more than two grooves may be used and the fabric may be twilled. A suitable take-up will carry away the completed hose.

The grooves shown are circular, and placed eccentrically as usual; but by cutting away the walls of pieces m m^1 to a sufficient distance, (see dotted lines,) I may make the grooves or paths more or less irregular or cam-shaped, and the crossings may take place at any desired intervals, the free ends of the inclined pivoted feet being adapted to be swung by the projections n and ends l^2 of pieces l , or equivalent pieces of other than crescent-shape between the grooves, the free ends of the pivoted feet passing into the spaces cut away in the side walls of the grooves.

It is evident the angle formed by the grooves at their crossings may be, under this arrangement, more or less sharp.

It will be understood that at the crossing points of the grooves, as herein shown and described, the grooves do not in curvature accord with the curve of the pivoted feet, and the spaces formed by cutting away the walls of the grooves permit the ends of the feet to move therein.

I claim—

1. The warp carrier-actuating plate, its projections n , pieces m m^1 , and ends l l^2 of different sizes, in combination with the warp-carriers and the inclined pivoted feet to operate the carriers quickly, substantially as described.

2. The combination, with the warp-carrier, of an adjustable thread-holding or nipping device, and a weight to operate the thread-holder, substantially as described.

3. A guide and mandrel to form and fold a lining of india-rubber, and warp and weft carriers adapted to weave a tubular covering about the lining, in combination with a cup to deliver a rubber or other cement on the outside of the folded lining.

4. The cup and steam-heated mandrel, separated therefrom, but within the cup, in combination with a pipe for discharging chalk or equivalent within the folded lining, substantially as and for the purpose described.

5. A guide and mandrel adapted to fold a strip of india-rubber into tubular form, in combination with a cup to contain liquid rubber to be expressed or applied to the outside of the folded rubber tube, substantially as described.

6. The mandrel and folding guide adapted to fold and lap the edges of a strip of india-rubber, to form a tube in combination with warp and weft carriers and mechanism adapted to operate them, to weave a tubular covering on the folded and lapped tube, substantially as described.

7. The carriers and inclined pivoted feet connected at one end with the carriers, in combination with a grooved plate having the side walls of the grooves cut away below the top surface of the plate, to receive the free ends of feet thrown into such open spaces, when the curvature of the grooves does not accord in curvature with the foot.

In testimony whereof, I have signed my name to this specification in the presence of two subscribing witnesses.

JAMES E. GILLESPIE.
